UNITED STATES PATENT OFFICE

HERBERT G. GOSLIN, OF BATTLE CREEK, MICHIGAN

ROOFING

Application filed March 28, 1929. Serial No. 350,465.

My invention relates to roofing and includes among its objects and advantages the development of a shingle that can be laid with the maximum coverage consistent with a predetermined head lap and side lap either as a lock shingle or as an ordinary shingle, and produce an attractive design in both instances. In the accompanying drawings, Fig. 1 is a diagram indicating how shingles according to the invention can be cut from a continuous strip of material without any waste.

Fig. 2 is a plan view of a portion of a roof with the shingles interlocking.

Fig. 3 is a plan view of a portion of a roof in which the same shingles are laid without interlocking and with less head lap to make a two-thickness roof.

In the embodiment of the invention selected for illustration each shingle comprises a substantial rectangular body 10 of materially greater height than width. The sides of the body are offset at 12 midway between the top and the bottom of the shingle. At the lower end of the shingle the sides flare outwardly to produce locking tabs 14 and the method of cutting requires a corresponding indentation at 16 at the upper corners of the shingle.

Shingles according to the invention may be laid according to Fig. 2 in which each shingle has its locking tabs 14 hooked under the offsets 12 of two shingles in the course below. Thus the shingle 18 has tabs at 20 underlying two shingles in the course below.

Above the level of the tabs 20 the body of the shingle 18 overlies the upper portions of the shingles in the course below as at 22. This overlap continues to the extreme top of the underlying shingle at the point 24, but it is further supplemented from the point 26 up by the shingles 28 in the course above which lap over the upper portion of the shingle 18. Thus there is always a side lap equal to that at 22, and before this is cut down by the recess at 16 in the underlying shingle the new side lap for the next course beginning at the point 26 fully protects the vertical joint.

By placing the offset 12 at the middle of the shingle, I secure a head lap at 30 equal to ex-

actly twice the height of the locking tab 14. This lap is greater than the side lap, a feature which is considered necessary in practical service to prevent wind from beating rain and moisture up under the lower edges of the shingles.

When the shingles are laid the other end up as in Fig. 3, they may be spaced apart laterally in each course by a spacing identical with that of Fig. 2 and the vertical spacing may be identical with that of Fig. 2 and in which case a coverage identical with that of Fig. 2 will be obtained. However, it is also possible to decrease the lateral spacing and the vertical spacing to a point such that no point on the roof is covered by less than two thicknesses of material. This is indicated in Fig. 3 where the upper end of shingle 32 extends up to exactly the same level as the lower end of shingle 34. Where the conditions of service or the requirements of durability call for a two-thickness roof, it is customary to increase the side lap to secure durability in that respect increased in proportion to the change in the head lap. When this is done, as indicated in Fig. 3, the exposed area of the shingle is broken up from a simple block T shape by the notches at 16.

It will be evident that the same type of T-shape with notched corners will be obtained in laying shingles according to the system of Fig. 3 but with head and side lap according to Fig. 2, except that the stem and the cross piece of the T will both be materially thicker.

When laid according to Fig. 2, the shingles cover as much area as possible with a single thickness of material only. Roofing according to Fig. 2 is generally suitable on old roofs previously covered with shingles or otherwise, and is commonly referred to herein and in the trade as a "single thickness" roof. When laid according to Fig. 3, the completed roof has no area covered by less than two thicknesses of material. Such a roof is referred to herein and in the trade as a "double thickness" roof and is suitable for new construction.

Shingles according to the invention, 21 inches high and having an average width of 100

14 inches, require 144 square feet of material per 100 square feet of roof surface, when laid according to Fig. 2; and 244 square feet when laid according to Fig. 3.

5 However, such large shingles are unsightly and difficult to sell, and the large area puts too heavy a load on the fastenings and the material. I prefer to make my shingle 16 inches high with an average width of 12 inches. In this size it requires 160 square feet for 100 square feet of single thickness roof according to Fig. 2; and 253 square feet for the double thickness roof of Fig. 3.

10 15 Without further elaboration, the foregoing will so fully explain my invention, that others may, by applying current knowledge, readily adapt the same for use under various conditions of service.

20 I claim:
25 1. A flexible shingle of generally rectangular shape defined by vertical side portions each offset by a single horizontal shoulder at mid-height of the shingle to form a broad and narrow portion, and locking tabs at the 30 end corners of the narrow portion, the vertical height of the tabs at their butts being sufficient to produce the proper vertical end overlap in a single thickness roof when the shingles are laid wide spaced in interlocked 35 relationship with the broad portions uppermost, the sides of the shingle being complementary when reversed end for end and laid side by side on the parent sheet for cutting without waste, the width of the shoulder being not more than one-sixth of the average width of the shingle.

40 2. A flexible shingle of generally rectangular shape defined by vertical side portions each offset by a single horizontal shoulder at mid-height of the shingle to form a broad and a narrow portion, and locking tabs at the 45 end corners of the narrow portion, the vertical height of the tabs at their butts being sufficient to produce the proper vertical end overlap in a single thickness roof when the shingles are laid wide spaced in interlocked 50 relationship with the broad portions uppermost, the sides of the shingle being complementary when reversed end for end and laid side by side on the parent sheet for cutting without waste, the width of the shoulder being not more than one-sixth of the average width of the shingle, whereby a continuous 55 side edge overlap may be attained when laid in a two thickness roof with the broad portions lowermost.

In testimony whereof, I have signed my name to this specification.

60 HERBERT G. GOSLIN.
